UNITED STATES PATENT OFFICE.

JAMES L. MALLORY, OF EVANSTON, ILLINOIS.

SCREEN.

No. 869,815.

Specification of Letters Patent.

Patented Oct. 29, 1907.

Application filed September 11, 1905. Serial No. 277,929.

To all whom it may concern:

Be it known that I, JAMES L. MALLORY, a citizen of the United States, residing at Evanston, in the county of Cook and State of Illinois, have invented certain new 5 and useful Improvements in Screens, of which the following is a specification.

My invention relates to improvements in screens, and has for its object the production of a simple and durable screen and one that is adapted to rid a dwelling of all 10 objectionable winged insects.

A further object is the production of a screen that, while affording all the advantages above described, presents no different appearance from an ordinary screen.

These and such other objects as may hereafter appear are obtained by my invention, one embodiment of which is illustrated in the accompanying drawings, in which

Figure 1 illustrates a front elevation of my improved screen. Fig. 2 shows a vertical sectional detail along 20 the line 2--2 of Fig. 1. Fig. 3 shows a similar detail of a modified embodiment of my invention.

Like letters of reference indicate like parts in the several figures of the drawing.

Referring by letter to the accompanying drawings, A 25 represents the frame of a window screen, B the bead surrounding said frame and holding the screen material C in place.

The screen surface C is composed preferably of two sections or members c' c'', so arranged as to leave a horizontal opening between the inner ends thereof, as at D, 30 and preferably arranged in substantially the same vertical plane.

In Fig. 2 the upper portion of the lower screen member c' is pivoted at h and a lever l is secured thereto, 35 whereby the upper movable portion m can be swung inwardly against the upper member c'', thus closing the channel f'.

It is evident that there are various modifications that can be made in this device, the essential element of 40 which is the making of the screen in sections, preferably two in number, and leaving between the adjacent ends of the sections an opening, preferably extending entirely across the screen surface and providing means whereby one screen section may be swung open or closed. Thus, as shown in Fig. 3, the upper screen member c' may be secured to a support which is pivoted at H and a lever such as the bell-crank lever L may be secured to the side of the frame and in engagement with the screen member c' whereby such member may be 45 50 swung upwardly until the portion G abuts the upper

portion of the lower member c'' at M thus closing the horizontal channel between the screen members.

It will be seen that my invention possesses two characteristic features, first the channel between the screen members may be readily opened and closed by the 55 movement of a pivoted lever regardless of whether or not the screen members are in substantially the same plane, and, second, the screen members may be arranged in substantially the same plane so as not to unnecessarily complicate the screen structure and at the 60 same time the channel between the screen members may be opened or closed in any suitable manner, and any suitable locking mechanism may be used to hold the movable screen member in open or closed position.

It is a fact capable of demonstration that winged insects when striking against or lighting upon a screen attempt to escape upward. This being the case, any opening provided in a screen through which the insects may make their way outside of the room will serve to automatically rid a room of their presence. 65

By providing an opening in a screen as shown, I take advantage of the fact that flies and like insects usually walk upwards upon a screen. Consequently they will walk upwards through the opening and escape. Whenever as to enter through the screen they must walk downwardly, consequently few, if any, insects will enter in that manner, especially if, as in my preferred construction, the passage through the screen be arranged near the upper edge of the screen. 70

Obviously, both screen members need not be made 80 of screening.

I claim:

1. The combination of a frame, two screen members mounted thereon and overlapping each other so as to provide a passage therebetween, one of said overlapping 85 parts being movable, and a lever pivoted to said frame and secured to said movable overlapping part whereby the said passage may be opened and closed at will.

2. The combination with a frame of two screen members the main parts of which are mounted in said frame 90 and in substantially the same plane, said screen members being arranged with overlapping edges whereby a passage is provided therebetween, one of said edges being movable and a pivoted member to which said movable edge is secured so that said passage may be opened or closed at 95 will.

3. The combination with a frame, of a fixed screen section, a movable section in the same plane with the fixed section when in its closing position, and means for moving the movable section out of alignment with the 100 fixed section so as to leave a space between the same.

JAMES L. MALLORY.
